UNITED STATES PATENT OFFICE

EARL T. ARNAULT, OF TACOMA, WASHINGTON

DESIGN FOR A WALL CLOCK

Application filed July 27, 1932. Serial No. 44,455. Term of patent 3½ years.

To all whom it may concern:

Be it known that I, EARL T. ARNAULT, a citizen of the United States, residing at Tacoma, in the county of Pierce, State of Washington, have invented a new, original, and ornamental Design for a Wall Clock, of which the following is a specification, reference being had to the accompanying drawing, forming part thereof,

In the drawing, Fig. 1 is a front elevation and Fig. 2 is a side elevation of a wall clock, showing my new design.

I claim:

The ornamental design for a wall clock, as shown.

EARL T. ARNAULT.
